SELF-PROPELLED TRUCK CRANE

John L. Grove, Greencastle, Pa., assignor to Grove Manufacturing Company, Shady Grove, Pa., a corporation of Pennsylvania

Filed Feb. 27, 1968, Ser. No. 10,747

Term of patent 14 years

Int. Cl. D12—05

U.S. Cl. D14—3

FIG. 3

FIG. 5

FIG. 4

FIG. 1 is a side elevational view of a self-propelled truck crane showing my new design, shown in traveling position;

FIG. 2 is a top plan view thereof;

FIG. 3 is a front elevational view thereof;

FIG. 4 is a rear elevational view thereof; and

FIG. 5 is a side elevational view, on a reduced scale, showing the side of the self-propelled truck opposite that of FIG. 1 and the same side of the crane of FIG. 1 in rotated position and in extended and elevated working position, the opposite side of the crane being substantially a mirror image.

I claim:

The ornamental design for a self-propelled truck crane, substantially as shown and described.
